CLAIM

The ornamental design for a transaction card, as shown and described.

DESCRIPTION

FIG. 1 is a top front isometric view of a transaction card showing the claimed design;

FIG. 2 is a top rear isometric view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines in the figures show portions of the transaction card that form no part of the claimed design.

The gray-shaded portions in the figures show a contrast in appearance with the non-shaded claimed portions.
